COMBINATION BIRD BATH AND SUPPORT FOR
FEEDERS AND SIMILAR ARTICLES

George M. Etnyre, Oregon, Ill.

Filed Feb. 3, 1964, Ser. No. 78,470

Term of patent 14 years

(Cl. D31—2)

FIGURE 1 is a top plan view of a combination bird bath and support for feeders and similar articles showing my new design;

FIG. 2 is an enlarged perspective view thereof; and
FIG. 3 is a side elevational view thereof.

I claim:

The ornamental design for a combination bird bath and support for feeders and similar articles as shown.
